CLAIM

The ornamental design for a shoe, as shown and described.

DESCRIPTION

FIG. 1 is a front perspective view of a shoe showing my new design;
FIG. 2 is a side view thereof;

FIG. 3 is a rear perspective view thereof;

FIG. 4 is a rear view thereof;

FIG. 5 is an opposite side rear perspective view thereof;

FIG. 6 is an opposite side view thereof; and,

FIG. 7 is a top view thereof.

The even-length broken lines within the shaded area represent stitching that forms no part of the claimed design. The uneven-length broken lines depicting the remainder of the shoe form no part of the claimed design.

1 Claim, 7 Drawing Sheets(56)
